UNITED STATES PATENT OFFICE.

ARNOLD F. GLASS, OF BIRMINGHAM, ALABAMA.

OIL OR GAS BURNING STOVE.

1,258,210.

Specification of Letters Patent. Patented Mar. 5, 1918.

Application filed June 29, 1916. Serial No. 106,658.

To all whom it may concern:

Be it known that I, ARNOLD F. GLASS, a citizen of the United States of America, residing at Birmingham, in the county of Jefferson and State of Alabama, have invented 5 certain new and useful Improvements in Oil or Gas Burning Stoves, of which the following is a specification.

This invention relates to an improvement 10 in stoves and ranges which are adapted to be heated by liquid or gaseous fuel burners.

The object of my invention is to design 15 an oil or gas burning stove which will have all of the advantages, as well as the wide range of usefulness, of the stoves and ranges 20 as now designed for burning coal and wood, and which in addition thereto will have many other advantages which can be derived from the novel methods which I propose for controlling the flow of the products 25 of combustion both around and through the oven of the stove.

One object of my invention is to design 30 a stove of this type which will have the general appearance of the hard fuel burning stoves, the fuel burners being disposed in the compartment which normally constitutes the fire box and ash-pit and they are arranged under removable lids in the stove 35 top. The products of combustion are caused to flow around the oven and enter the stove flue below the oven which is provided in one side and in its bottom with one or more series of holes which can be closed by sliding 40 dampers and which serve to admit the products of combustion into the oven so that they will flow therethrough to a supplemental inlet to the stove flue near the top of the oven. A novel damper is provided 45 for this supplemental inlet which serves the double function of controlling the draft through both inlet openings to the stove flue.

Another feature of my invention relates 50 to the provision of a high warming closet and the provision of suitable dampers to force the hot air into this closet and maintain it at the desired temperature.

My invention also comprises the various 55 novel features of construction and arrangements of parts which are hereinafter more particularly described and illustrated in their preferred embodiment only, but which, as set forth in the claims, may be widely varied without departing from my invention.

Referring to the drawings:

Figure 1 is a top plan view of an oil burning stove in accordance with my invention, having the stove top and the oven 60 top broken away to illustrate the internal arrangement of parts.

Fig. 2 is a front elevation of Fig. 1 with a high warming closet added.

Fig. 3 is a sectional view taken on the 65 line 3—3 of Fig. 2.

Fig. 4 is a detail view of a section of the oven bottom showing one of the side dampers for controlling the admission of hot air 70 into the oven.

Similar reference numerals refer to similar parts throughout the drawings.

The stove may be made of any suitable material but is preferably made of sheet metal shaped to form a bottom 1, end walls 75 2 and 3, a front wall 4, and a back wall 5. The top 6 is a casting having removable center sections 6^a, 6^b, such as are in general use in stoves and ranges. As illustrated, the stove body is in the form of an oblong 80 rectangular sheet metal box supported on suitable legs 7 and provided with suitable holes in the top sections 6^a, 6^b to receive the removable stove lids 8. I provide an ordinary hinged front door 9 and in the end 85 wall 2 I provide a hinged downwardly swinging door 10 which is preferably provided with transparent panels so that the burners 11 in the fire-box 12 of the stove can be observed and which will also give 90 convenient access to the valves 13 by means of which the burners are controlled. As illustrated, the burners are adapted to burn kerosene or any suitable fuel oil which is contained in a tank 14 mounted on the back 95 wall 5 of the stove and from which leads a pipe 15 which supplies two burners 11 which are arranged under the two left hand lids 8, with the tops of their chimneys disposed slightly below the top wall of the 100 oven 16 and in position to heat the hot-water coil 17. At the left hand end of the oven I provide a vertical partition wall 18 which with the oven divides the fire-box 12 from the rest of the stove, leaving however 105 a top flue or passageway 19 through which the hot air from the burners flows over the oven and downwardly between the oven and the end stove wall 3 and back under the oven where it is deflected by a transverse inclined baffle 20, disposed between the oven 110 and the stove bottom 1, and caused to flow

toward the front wall 4 and then to pass rearwardly between the wall 18 and baffle 20 to the back wall 2 through which an outlet port 21, see Fig. 3, opens into the bottom 5 of the stove flue 22. This flue extends upwardly and flares outwardly at 23 and passes up through the rear edge of the top 6 which projects beyond the back wall 5 of the oven and forms a protection above the 10 oil tank 14.

The oven is rectangular in shape and has its top, bottom and sides provided with outward turned flanges 25 which are riveted or made fast to the back wall 5 of the stove. At their 15 front edges these oven walls have like outward turned flanges which are made fast to the front wall 4 of the stove, the oven thus being formed by a rectangular strip of sheet metal spaced from the top, bottom and side 20 wall of the stove and made fast to the front and back walls of the stove body which form its front and back walls. The stove flue 22 is likewise formed by attaching a flanged U-shaped member of sheet metal to the back 25 wall 5 of the stove and providing at the upper end of the member an annular nipple 26 which projects through and above the top 6 of the stove and receives the stove pipe 24.

In the upper portion of the right hand 30 side wall of the oven and at one or more points in its bottom I provide a transverse series of holes or ports 27 and I control each series of holes by a sliding ported damper 28, the front end of which projects 35 through the front wall 4 of the stove and is provided with a hook-like handle 29. The damper is held in position by metal straps 30 and 31 substantially Z-shaped in cross section and which are reversed and have their bottom flanges inturned and spaced from the oven wall and from each other to form 40 guides for the side edges of the damper. The straps 31 are provided with a flange 32 which is inclined downwardly and in a direction counter the flow of the gases. It 45 thus serves as a deflecting baffle which will tend, when the damper is open, to deflect the hot air into the oven. I provide at the top of the oven an outlet port 33 which 50 opens into the flue 22 and below this opening in the flue I hinge a damper 34 which

is controlled by a crank 35 and a damper handle 36 which passes up through the top of the stove and is notched to set the damper either in position to close the port 33 or to 55 open the flue 22 above port 21, or to open port 33 and close the flue 22, thereby closing the bottom port 21. The damper has a neutral position in which, as shown in Fig. 3, the stack is drawing hot air through both 60 ports 21 and 33.

When I desire to provide the stove with a high warming closet 37, the latter is mounted on a back plate 38 which is attached to the top 6 behind the pipe 24, which 65 passes up through the warming closet and is provided therein with a damper 39 through which the hot air can gain access to the closet. Above the closet I provide a damper 40 and by partly closing this damper 70 the volume of hot air forced into the warming closet through the damper 39 can be varied. At each end of the stove I provide suitable hinged shelves 41.

Having thus described my invention, what 75 I claim as new and desire to secure by Letters Patent, is:

1. In a stove, a fire-box, gaseous burners therein, an oven, there being a flue leading from the fire-box over and down by and 80 back under the oven, a stack pipe connected with said flue below the oven and having a port opening into the upper part of the oven, side and bottom dampers to admit hot air from said flue into the oven, and a 85 damper valve for said port which also controls the flow of hot air through the stack from below the oven.

2. In a stove, gaseous burners, an oven, a 90 down draft flue through which the hot air passes around the oven, a stack flue connected with the down draft flue below the oven and with the oven, means to divert hot air from the down draft flue into the oven, and a damper in the stack flue movable to 95 shut off the connection to the oven or the down draft flue, substantially as described.

In testimony whereof I affix my signature.

ARNOLD F. GLASS.
